BY *Victor J. Evans*

ATTORNEY

WITNESS: *Fred. W. Ely.*

UNITED STATES PATENT OFFICE.

ALFRED H. EVANS, OF NEW YORK, N. Y.

COLLAPSIBLE CONCRETE MOLD.

Application filed September 9, 1922. Serial No. 587,152.

To all whom it may concern:

Be it known that I, ALFRED H. EVANS, a citizen of the United States, residing at Bronx, in the county of Bronx and State of New York, have invented new and useful Improvements in Collapsible Concrete Molds, of which the following is a specification.

This invention relates to collapsible concrete molds.

An object of the invention is to provide a mold which, when set-up will be strong and durable and wherein the walls or sections of the structure will divide the latter into a plurality of cells of uniform size, the construction of the parts being such as to give to the walls of each cell maximum rigidity and strength so as to hold the walls against undue sagging under the weight of the concrete when placed in the cells during the molding operation.

A still further object of the invention is to provide a collapsible mold which can be set-up or knocked down with dispatch as the occasion requires.

Another object of the invention is to provide novel means for securing the walls of the mold together when the structure is set-up.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of the mold set-up.

Figure 2 is a longitudinal section through a portion of the mold.

Figure 3 is a perspective view of one of the end walls.

Figure 4 is a perspective view of one of the locking bars carried by the end wall.

Figure 5 is a perspective view of one of the units of one of the intermediate walls.

In carrying the invention into practice, use is made of a plurality of identically constructed longitudinal walls 4. Four of these walls are shown for the purpose of illustration but it will be understood that I may increase or decrease this number to suit various purposes and conditions. The walls 4 are provided with core openings 6 and when the mold is set-up the openings in one

wall coincide with the openings of another or adjacent wall as shown in Figure 1. Any suitable well-known form of core may be used in connection with the mold. The longitudinal walls are formed at their ends with T-shaped slots 7. Two of these slots are preferably arranged at each end of each of said walls and the same are superimposed as shown in Figure 2. The purpose of this construction will be described hereinafter. Associated with the longitudinal walls are identically constructed end walls 8 slotted at 9 along their central portions and slotted at 10 and 11 respectively along their upper and lower edges and in vertical alignment with the aforesaid slots 9 as shown in Figure 3. From this construction the ends of the longitudinal walls may be operatively projected through the mating slots 9, 10 and 11 when setting the mold up.

On each end wall 8 are sliding locking bars 12 and 13 operatively connected at 14 with a rocking lever 15. This lever is pivoted at 16 to the lower edge of said wall so that when the lever is rocked the bars 12 and 13 will be simultaneously moved in the same direction. These lock bars are provided with substantially H-shaped sections 17 of relatively increasing proportions from one end of each of said locking bars to the other end thereof. These bars are adapted to be projected into the T-shaped slots 7 as shown in Figures 1 and 2 when the mold is set-up. Each of the H-shaped portions 17 is provided with a connecting cross-piece 18 adapted to be passed through the restricted branch 7a of the adjacent slot 7 in associating the longitudinal walls 4 with the end walls 8.

In setting-up the mold I first arrange the walls 8 at a proper distance with respect to each other and then successively connect the longitudinal walls 4, starting from the outside of the mold and working inwardly until the opposite side of the mold is built up. Also in succession with the operation of connecting the longitudinal walls 4 with said end walls I actuate the levers 15 so as to bring the main locking portions 19 of the bars 12 and 13 into locking engagement with said slots 7. In this manner the longitudinal walls may be firmly interlocked with the mating end walls 8. The said longitudinal walls are also held equidistantly spaced apart.

In order to divide the mold into a mul-

tiplicity of cells of uniform size I employ intermediate transverse walls 20, each consisting of a number of separable units provided in their upper edges with recesses 21 adapted to register horizontally with recesses 22 in the longitudinal walls 4. These units are arranged between the walls 4 as clearly shown in Figure 1. The lower ends of these units are provided with recesses 23 which register with slots 24 in the walls 4. Through the slots 24 and adapted to be engaged in the recesses 23 of each of said intermediate walls is a transverse locking bar 24' which is held against accidental disarrangement by latch devices 25 on the outer walls 5. The recesses 21 and 22 receive locking bars 26. When all of the parts are connected as shown in Figure 1 the mold is set-up ready for use and its base can be mounted upon any suitable flat platform ready for the pouring operation. The units 21 as shown in Figures 2 and 5 are offset at their sides as at 27. The end walls 8 are correspondingly offset at 28. Through this arrangement each molded block will be provided with end cavities.

After blocks have been formed the several sections of the mold may be easily disassembled as will be understood.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A collapsible mold comprising longitudinal walls, end walls, means on the end walls co-acting with said longitudinal walls to hold the mold set up, intermediate walls detachably associated with the longitudinal walls for dividing the mold into a plurality of non-communicating cells, said intermediate walls consisting of relatively separable units, and means connected with the longitudinal walls and co-acting with said units to hold same in set up positions.

2. A collapsible mold comprising longitudinal walls, end walls, means on the end walls co-acting with said longitudinal walls to hold the mold set up, intermediate walls detachably associated with the longitudinal walls for dividing the molds into a

plurality of non-communicating cells, said intermediate walls consisting of relatively separable units, means connected with the longitudinal walls and co-acting with said units to hold same in set up positions, said holding means consisting of bars carried by the longitudinal walls and receivable in recesses formed in said units.

3. A collapsible mold comprising longitudinal walls, end walls, means on the end walls co-acting with said longitudinal walls to hold the mold set up, intermediate walls detachably associated with the longitudinal walls for dividing the molds into a plurality of non-communicating cells, said intermediate walls consisting of relatively separable units, means connected with the longitudinal walls and co-acting with said units to hold same in set up positions, said holding means consisting of bars carried by and detachable from said longitudinal walls and receivable in recesses formed in said units.

4. A mold consisting of longitudinal walls and connecting end walls, the end walls having slots for the reception of the extremities of the longitudinal walls, sliding locking bars carried by the end walls and co-acting with the extremities of the longitudinal walls to hold same operatively secured to said end walls, and levers pivoted to said end walls and said bars to actuate the latter.

5. A mold consisting of longitudinal walls and connecting end walls, the end walls having slots for the reception of the extremities of the longitudinal walls, sliding locking bars carried by the end walls and co-acting with the extremities of the longitudinal walls to hold same operatively secured to said end walls, said locking bars including substantially H-shaped separated portions, the extremities of the longitudinal walls having slots therein co-acting with said H-shaped portions.

6. A mold comprising longitudinal walls having slotted extremities, end walls having portions through which the extremities are extended, means on the end walls for successively locking and unlocking the extremities of the longitudinal walls with respect to said end walls, and levers pivoted to said end walls and said means to actuate the latter.

In testimony whereof I have affixed my signature.

ALFRED H. EVANS.
